UNITED STATES PATENT OFFICE.

CLAUDE SIEBRING, OF GEORGE, IOWA.

SWINGING GATE.

No. 805,032.

Specification of Letters Patent.

Patented Nov. 21, 1905.

Application filed August 10, 1905. Serial No. 273,576.

To all whom it may concern:

Be it known that I, CLAUDE SIEBRING, a citizen of the United States, residing at George, in the county of Lyon and State of Iowa, have 5 invented a new and useful Swinging Gate, of which the following is a specification.

The invention relates to improvements in swinging gates.

The object of the present invention is to improve 10 the construction of swinging gates and to provide a simple and comparatively inexpensive one of great strength and durability adapted to be readily opened and closed at a distance from either side of it to avoid dismounting from a horse or leaving a vehicle.

A further object of the invention is to provide 15 a gate of this character which when closed will be firmly locked in such position to prevent hogs and cattle from opening it.

With these and other objects in view the invention consists in the construction and novel combination and arrangement of parts herein-after fully described, illustrated in the accompanying drawings, and pointed out in the 25 claims hereto appended, it being understood that various changes in the form, proportion, size, and minor details of construction within the scope of the claims may be resorted to without departing from the spirit or sacrific- 30 ing any of the advantages of the invention.

In the drawings, Figure 1 is a perspective view of a swinging gate constructed in accordance with this invention and shown closed. Fig. 2 is a side elevation, the gate being open. Fig. 3 is a vertical sectional view on the line 35 3 3 of Fig. 2.

Like numerals of reference designate corresponding parts in all the figures of the drawings.

1 designates a swinging gate consisting of 40 a frame of tubular metal and vertical and horizontal wires; but any other form of gate may be employed, as will be readily understood. The gate is hinged to a post or support 2 by 45 means of upper and lower hinges having elongated pintles 3, mounted on the post or support 2 and receiving slidable eyes 4, fixed to the gate and adapted to permit the latter to be raised and lowered, as hereinafter explained.

The elongated pintles may consist of enlarged 50 staples secured to the hinge post or support; but they may be constructed in any other desired manner.

The gate, which is lifted by the means here-

inafter explained, is provided at its outer end 55 with a latch projection 5, adapted to engage a fixed keeper 6 of a latch-post 7. The fixed keeper, which is provided at its upper face with a recess 8 to receive the projection 5 of the gate, has an inclined or beveled upper edge 60 9 extending from its outer end to the recess for permitting the projection 5 to slide readily over the keeper when the gate closes. When the gate is closed and the projection 5 is in engagement with the keeper, it is securely 65 locked, and as the hinged end of the gate is slidable on the hinge-post by means of the eyes and the elongated pintles it is necessary in order to open the gate to lift the same at a point adjacent to the inner or hinged end of 70 the gate to prevent the members of the hinge from binding.

The gate is lifted vertically and oscillated horizontally by means of an upwardly-extending oscillatory lever 10, consisting of a tubular bar or member fulcrumed at its lower end and provided at its upper end with an angularly-disposed arm 11. The lower end of the tubular bar or member is provided with an eye 12, which is linked into an eye 13 of a 80 support 14, consisting of a short post or stake driven into the ground and having its upper end arranged at the surface thereof. The eyes may consist of eyebolts having shanks embedded in the support 14 and secured in the 85 lower end of the tubular bar or member 10. The post or support 14 is located at a point in advance of the transverse plane of the hinges of the gate, and when the latter is open, as illustrated in Figs. 3 and 4 of the drawings, 90 the lower portion 15 of the tubular bar or member extends a considerable distance in advance of the gate. The lower portion is curved or bent to arrange it at an angle to the body portion of the tubular bar or member and to 95 enable it to extend beneath the gate when the latter is open. The arm 11, which is arranged at right angles to the main portion of the bar or member 10, is preferably constructed of flat metal and is suitably secured to the upper 100 end of the tubular bar or member, preferably by means of a fastening device embedded in a wooden plug fitted in the upper end of the tubular bar or member. The arm 11 is supported by an inclined brace 16, extending from 105 the central portion of the tubular bar or member to the outer portion of the arm 11.

The outer end of the arm 11 is provided

with an eye 17, which is slidably connected with the top of the gate by means of a loop-shaped guide 18, extending longitudinally of the gate and having a horizontal top portion 5 and provided with vertical sides. The sides terminate at their lower ends in eyes or sleeves 19, which embrace the top of the frame of the gate and which are suitably fixed to the same; but the guide may be secured to the gate in 10 any other desired manner.

The gate-actuating lever is arranged at an inclination when the gate is closed, as illustrated in Fig. 1 of the drawings, and when the lever is swung rearward the arm 11 moves upward and operates to lift the gate. The slideable connection between the end of the arm and the gate permits the lever to move the gate vertically before swinging the same horizontally. This vertical movement of the gate 15 unlatches the same by carrying the projection 5 upward out of engagement with the keeper. The continued rearward movement of the lever swings the gate horizontally and carries the same to its open position. The lever by 20 this movement is carried beyond a perpendicular position and its weight tends to maintain the gate in its open position, as clearly shown in Fig. 3 of the drawings. The gate while open is in an elevated position, as clearly 25 shown in Fig. 2 of the drawings, and when the lever is swung outward by the means herein-after described the weight of the gate and the lever will complete the closing movement of the former, whereby the gate is positively 30 opened and closed. The gate-actuating lever is connected with a pair of operating-levers 35 20 and 21 by means of a wire rope or cable 22 or other flexible connection secured at one end to the arm of the gate-actuating lever and 40 provided at its other end with two branches 23, which are secured to the inner ends of the operating-levers. The arm 11 of the gate-actuating lever is provided with an eye 24 to receive the front or lower end of the flexible 45 connection 22. The eye 24 preferably consists of an eyebolt the shank of which pierces the arm 11, being headed or otherwise secured at the inner or lower face of the arm 11. The operating-levers, which extend longitudinally 50 of the roadway, are fulcrumed between their ends and are provided at their outer ends with suitable handles 25 for enabling them to be readily grasped by a person on horseback or in a vehicle. The lever 20 is fulcrumed on a 55 post or upright 26 and the other lever 21 is fulcrumed on an inclined bar 27, secured at its lower end to and extending upwardly and outwardly from the hinge post or upright. The posts or uprights 2 and 26 are connected 60 by a horizontal bar 28, which also extends beyond the hinge post or upright to brace the inclined bar 27. A guide-pulley 29 is mounted on the horizontal bar 28 in a suitable bracket 30, and its lower edge extends below 65 the plane of the horizontal bar to prevent the

flexible connection from coming in contact with the same in the closing operation of the gate.

When the gate is open, the lower portion of the flexible connection extends rearwardly 70 from the guide-pulley at an inclination so that it is adapted to exert a direct forward pull on the oscillatory gate-actuating lever sufficient to impart to the gate the necessary momentum to carry the gate to its closed position. 75

Having thus fully described my invention, what I claim as new, and desire to secure by Letters Patent, is—

1. The combination of a swinging gate, an upwardly-extending oscillatory gate-actuating lever fulcrumed at its lower end in advance of the point of hinging of the gate and at one side of the same when the gate is in its closed position, said lever being provided at its lower end with an arm extending beneath 80 and in advance of the gate when the latter is in its open position, means for connecting the lever with the gate, and operating mechanism connected with the lever for oscillating the same. 90

2. The combination of a swinging gate, an upwardly-extending oscillatory gate-actuating lever fulcrumed at its lower end in advance of the point of hinging of the gate and at one side of the same when the gate is in 95 its closed position, said lever being provided at its lower end with an arm extending beneath and in advance of the gate when the latter is in its open position, an arm arranged at the top of the lever and connected with the 100 gate, and operating mechanism for oscillating the lever.

3. The combination of a vertically-movable horizontally-swinging gate, a lever fulcrumed at its lower end in advance of the hinges of the gate and located at one side of the latter when the gate is closed, said lever being provided at its lower end with an arm extending beneath and to a point in advance of the gate when the latter is in its open position, means for slidably connecting the upper portion of the lever with the gate, and operating mechanism for actuating the lever. 110

4. The combination of a vertically-movable horizontally-swinging gate, a lever fulcrumed at its lower end in advance of the hinges of the gate and located at one side of the latter when the gate is closed, said lever being provided at its lower end with an arm extending beneath and to a point in advance of the gate 115 when the latter is in its open position, a guide mounted on the gate and extending longitudinally thereof, and an arm extending from the top of the lever and slidably on the guide. 120

5. The combination of a vertically-movable horizontally-swinging gate provided with a horizontal guide, an upwardly-extending lever fulcrumed at the lower end and provided at the top with an arm slidably on the guide, operating mechanism connected with the lever, 125 130

and a latch operated by the vertical movement of the gate for locking the latter in its closed position.

6. The combination of a vertically-movable horizontally-swinging gate, an upwardly-extending lever fulcrumed at its lower end at a point in advance of the hinges of the gate and provided at the bottom with an arm extending beneath and in advance of the gate when the latter is open, a guide carried by the gate, an arm extending from the top of the lever and slidably on the guide, and operating mechanism for oscillating the said lever.

7. The combination of a vertically-movable horizontally-swinging gate, a latch operated by the vertical movement of the gate, a gate-actuating lever fulcrumed at the bottom and extending upwardly to and slidably connected with the top of the gate, operating-levers, a

flexible connection extending from the gate-actuating lever to the operating-levers, and means for guiding the flexible connection.

8. The combination with a vertically-movable horizontally-swinging gate provided with a guide extending longitudinally of the gate, an upwardly-extending lever fulcrumed at its lower end and slidably connected at the top with the guide, means for actuating the lever, and a latch operated by the vertical movement of the gate for locking the latter in its closed position.

In testimony that I claim the foregoing as my own I have hereto affixed my signature in the presence of two witnesses.

CLAUDE SIEBRING.
